UNITED STATES PATENT OFFICE.

LESTER C. HART, OF CLEVELAND, OHIO, ASSIGNOR TO HI-VOLTAGE EQUIPMENT COMPANY, A CORPORATION OF PENNSYLVANIA.

INCLOSED FUSE.

Application filed April 24, 1925. Serial No. 25,539.

The invention relates to fuses, and particularly to fuses of the expulsion type in which the fuse is carried or housed in a tube or a tubular member. It has for one of its 5 principal objects, the provision of a fuse of the type specified, which is reliable under all conditions of service, and which will operate either with a light overload current, or with a very heavy overload without destroying any of the parts other than the fuse wire itself. It has for a further and most important object the provision of a construction which will unfailingly secure an extinction of the arc after the fuse has 10 blown. The fuse is illustrated and described in one relation, namely, with an upright mounting, but may be used in other relations and in other positions depending upon conditions. In the embodiment of the invention 15 illustrated:

Figure 1 is a perspective view of the parts in assembled relation. And Fig. 2 is an enlarged longitudinal section through the fuse tube.

Referring to the drawings, 1 is a base plate carrying the insulator posts 2 and 3, upon which are mounted the insulators 4 and 5. These insulators are provided with the metal caps 6 and 7, which constitute the terminals 30 of the mains 8 and 9.

The cap or terminal 7 has rigidly secured thereon the metal yoke 10 having at one end the hooks 11, and at the other end, the split collar 12 clamped around the fuse tube, as 35 indicated in Fig. 1. The fuse tube is made up of the casing 13 of metal and the tube 14 of insulating material, which latter is threaded into the casing 13. The casing 13 is provided with a pair of laterally projecting lugs 15 carried in the hooks 11. The lug and hook connections 11 and 15 in connection with the split collar 12 provide a convenient means for securing the tube in position and releasing it.

The casing 13 is closed by means of the plug 16, also of metal, which carries the lug 17 in which is mounted the binding screw 18. This screw clamps the end of the fuse wire 19, such fuse wire extending through the 50 tube 14 and being connected at its end to the terminal or cap 6 and to the main 8. The fuse wire is preferably smaller in cross section at the end in the casing 13 than elsewhere, so that in case of an overload, this 55 portion of the wire is burned out first, form-

ing a vapor in the chamber 20, and developing a pressure high enough to blow out any wire remaining in the tube and clear it of gases with a considerable degree of explosive force. The use of the smaller cross section 60 of fuse wire (somewhat exaggerated in the drawing) in the chamber 20 facilitates this high speed clearing action. The force involved in the fusing action is such that a tube of great strength is required. The 65 metal casing 13 is exposed to the greatest strain, and this is made sufficiently strong to resist any explosive action to which it may be subjected. The tube 14 must also be made of a material of great strength, 70 which, at the same time, has high insulating qualities. These requirements are met by the use of bakelite, reinforced by layers of canvas or paper.

In order to protect the bakelite from the 75 heat generated by the electric arc, which is formed momentarily when the fuse blows, a liner 21 of refractory material, such as asbestos is provided. This liner, being protected by its position inside the tube, does 80 not need to possess the weathering qualities of the tube itself.

It will be noted that the fuse wire is supported in the chamber 20, so that it does not contact with the wall of the casing, which 85 arrangement renders the wire more reliable as to the fusing point for which it is designed than would be the case if it were allowed to touch the metal wall of the casing, it being recognized that a fuse wire surrounded and 90 insulated by quiet air is accurate in its action in accordance with its calibration, but that this is not the case, if it engages a conductor.

The device has sufficient strength to withstand violent explosions as developed by heavy sudden loads, and at the same time, the air space in the tube is so proportioned that when the device blows from a relatively light overload, sufficient pressure and velocity is developed to insure a successful breaking of the arc, which is formed, thus fulfilling the requirement for certainty of operation under the widest possible range of conditions.

The air gap, which is provided between the open end of the fuse tube 14 and the terminal 6, prevents the leakage of any current through the tube or over it after the fuse blows, and the force of the explosion 105 110

is such as to insure the clearing of the tube and the extinguishing of the arc, this action also being promoted by locating the terminal 6 out of alignment with the tube, so that the force of the explosion is directed over and away from the terminal, rather than against it. After the fuse has blown, the tube may be used again, the only part requiring replacement being the fuse wire.

10 What I claim is:

1. A fuse construction comprising a tube closed at one end and open at the other, supporting means at said closed end only, a fuse wire extending from the closed end 15 of the tube out through the open end of the tube, a terminal lying at a substantial distance to one side of the line of the tube and spaced away from the end thereof to provide a complete air gap between the tube 20 end and the terminal when the wire is fused, to which terminal the fuse wire is connected, a second terminal, and an electrical connection between such second terminal and the end of the fuse wire lying in the tube, the 25 space between the open end of the tube and the first mentioned terminal being free from any solid body aside from said wire.

2. In combination, a base, a pair of parallel insulator posts projecting from said 30 base, an insulator mounted on each of said posts, each provided at its outer end with a metal terminal, a fuse tube mounted at one end which is closed upon one insulator and with its other end open and extending 35 laterally to a point at one side of the other terminal, but spaced away therefrom to provide a complete air gap between the tube

and said other terminal and the insulator supporting it, and a fuse wire extending through the tube with one end having electrical connection with the terminal on the insulator carrying the tube and with its other end extending out through the open end of the tube where it turns laterally and is connected to said other terminal, the space 45 between the tube end and said other terminal being free from any solid body aside from the fuse wire.

3. In combination, a pair of parallel insulator supports in spaced relation, an insulator carried on each of said supports, a terminal carried by each insulator, a fuse tube closed at one end and open at the other, mounted on one of said insulators at its closed end and extending transversely 50 of said supports with its open end adjacent to the terminal on the other insulator, but unsupported by said last terminal or its insulator and out of alignment with such terminal, and a fuse wire extending through 55 the tube with one end lying in the closed end of the tube and having electrical connection with one terminal and with its other end extending out through the open end of the tube where it turns laterally and is connected to the other terminal, the space between the said open end of the tube and said other terminal being free from any solid body aside from the wire, thus giving a complete 60 air gap when the wire is fused.

In testimony whereof, I have hereunto subscribed my name this 16th day of April, 1925.

LESTER C. HART.
